UNITED STATES PATENT OFFICE.

JOSEPH B. KAUSAL, OF CHICAGO, ILLINOIS.

AISLE CHAIR.

Application filed January 19, 1925. Serial No. 3,235.

To all whom it may concern:

Be it known that I, JOSEPH B. KAUSAL, a citizen of the United States, and a resident of the city of Chicago, county of Cook, and 5 State of Illinois, have invented certain new and useful Improvements in Aisle Chairs, of which the following is a specification.

My present invention relates to aisle chairs, especially adapted for use in theaters, motion 10 picture houses, auditoriums, assembly halls, and similar places where there are gatherings of people, and the invention has for its paramount object the provision of an improved aisle chair having means for illuminating the aisle at the foot of the chair, and 15 having the source of the lighting concealed, so that there will be no glare to annoy the patrons.

Other objects will appear hereinafter. 20 The invention consists in the combinations and arrangements of parts hereinafter described and claimed.

The invention will be best understood by reference to the accompanying drawings 25 forming a part of this specification, and in which,

Fig. 1 represents a front elevational view 30 of an aisle chair embodying my improvements, parts being shown in section;

Fig. 2 represents a side elevational view 35 of the chair with parts in section;

Fig. 3 shows an enlarged cross section taken on line 3—3 of Fig. 2; and

Fig. 4 represents an enlarged vertical 40 sectional view through the lamp chamber, this view illustrating in particular the lamp holding plate and the closure plate as they appear when swung into open positions.

The preferred embodiment of my invention as illustrated in the accompanying 45 drawings comprises an aisle chair 5 of any suitable construction, having the usual seat and back parts 6 and 7, respectively, and the end standards 8 and 9, of which the 50 standard 9 represents the aisle standard in connection with which my improvements are exemplified.

Preferably and as shown, the aisle standard 9 includes a front leg 10 and a rear 55 hollow leg 11, the same being connected by a cross piece 12 above which is a panel connection 13 in the top portion of which, just below the arm rest 14, is provided a cavity or lamp chamber 15 having an open side 60 facing the aisle. Within this lamp chamber 15 is located a reflector comprising opposite

ends 16 and 17, a back plate 18 which merges through a curved portion 19 into a stop plate 20. 21 represents the bottom of this reflector which, as shown in Fig. 4, is inclined 65 downwardly and outwardly. With the lamp chamber thus provided, the hollow leg 11 has communication through an opening 22 provided therein, and a corresponding opening 23 provided in the adjacent end 17 of the 70 reflector.

Normally closing communication between the hollow leg and the lamp chamber is a plate 24 which is hinged at 25 to the end plate 17 and carries a lamp socket 26 for receiving an incandescent bulb as 27 of ordinary type. The hinged plate 24 is held in closed position by any suitable means such as a spring catch or detent 28. The hollow leg 11, in this construction, serves 75 as a conduit through which are taken the circuit wires 29 and 30 which may be brought underneath the floor from any suitable source of supply. These wires 29 and 30 are connected to the lamp socket in the usual way. By making the end standard with a hollow leg and by employing a hinged socket plate as described, the lamp chamber 80 may be relatively small, in width, since the lamp may be applied or removed by swinging the socket plate 24 upon its hinge from its normal position as shown in Fig. 3 to the position illustrated in Fig. 4, the hollow leg serving as ample room wherein the wire conductors 29 and 30 may be turned or coiled 85 upon themselves as at 29' and 30' thereby readily permitting their extension for the swinging of the lamp socket with the hinged plate.

The open side of the lamp chamber is 90 closed by a plate 31 which is hinged at 32 to the standard panel above said lamp chamber. This closure plate 31, when swung into closed position completely conceals the lamp; and it is formed with means for receiving the rays from the lamp and the reflector walls and then diverting or directing the rays downwardly alongside the standard 95 to illuminate the floor of the aisle there adjacent. In order to carry out this purpose, the closure plate 31 is formed intermediate 100 its side walls with an outwardly deformed or bulged region 33, which terminates in a curved extremity 34 below the lamp chamber. This outwardly offset deformation 33 105 is open at its lower end so that the rays of light which it gathers may be directed down-

wardly upon the aisle floor. The closure plate 31 may be readily swung upwardly as shown in Fig. 4, when it is necessary to swing the plate 24 into outward position for the removal or application of a lamp. This closure plate may be secured in its closed position by means of screws 35 or equivalent means.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A chair having a lamp chamber there-in open at one side, a lamp hinged within the chamber and adapted to be swung out through said open side, and a light-directing closure plate hinged to swing outwardly to allow the outward swinging of said lamp, substantially as described.

2. A chair having a lamp chamber there-in, a reflector in the chamber having a downwardly and outwardly inclined bottom, a lamp arranged in the chamber, and an outwardly offset light-directing part opposite said inclined bottom and having an opening exteriorly of the chamber, substantially as described.

3. In a chair, the combination with a lamp chamber and a hollow leg opening thereinto, a flat plate hinged to close said

opening and adapted to carry a lamp, and a closure plate for the lamp chamber having a portion offset therefrom and open to direct rays of light to the floor, said hollow leg constituting a conduit for the circuit wires, substantially as described.

4. In a chair, the combination with a lamp chamber having an open side, a plate hinged in the chamber and carrying a lamp, a hinged closure plate for the open side of the chamber and having an open light-directing portion, said closure plate on being opened clearing the way to allow said lamp holding plate to be opened, substantially as described.

5. In a chair, the combination with a standard having a hollow leg, of a lamp chamber communicating with said hollow leg, a plate hinged in the chamber and carrying a lamp, circuit wires extending through said hollow leg to said lamp, and a closure plate for said lamp chamber having a light directing portion, substantially as described.

6. In a chair, the combination with a standard having a hollow leg, of a lamp chamber communicating with said hollow leg, a hinged plate closing communication between said hollow leg and said chamber, a lamp on said plate, circuit wires extending through said hollow leg to said lamp, a plate hinged to the standard for closing the lamp chamber, and an outwardly offset portion on said plate for directing light from said chamber to the floor, substantially as described.

In testimony whereof I have signed my name to this specification.

JOSEPH B. KAUSAI.

wardly upon the aisle floor. The closure plate 31 may be readily swung upwardly as shown in Fig. 4, when it is necessary to swing the plate 24 into outward position for the removal or application of a lamp. This closure plate may be secured in its closed position by means of screws 35 or equivalent means.

While I have illustrated and described the 10 preferred form of construction for carrying my invention into effect, this is capable of variation and modification without departing from the spirit of the invention. I, therefore, do not wish to be limited to the 15 precise details of construction set forth, but desire to avail myself of such variations and modifications as come within the scope of the appended claims.

Having described my invention, what I 20 claim as new and desire to secure by Letters Patent is:

1. A chair having a lamp chamber therein open at one side, a lamp hinged within the chamber and adapted to be swung out 25 through said open side, and a light-directing closure plate hinged to swing outwardly to allow the outward swinging of said lamp, substantially as described.

2. A chair having a lamp chamber therein, a reflector in the chamber having a downwardly and outwardly inclined bottom, a lamp arranged in the chamber, and an outwardly offset light-directing part opposite said inclined bottom and having an 30 opening exteriorly of the chamber, substantially as described.

3. In a chair, the combination with a lamp chamber and a hollow leg opening thereinto, a flat plate hinged to close said

opening and adapted to carry a lamp, and 40 a closure plate for the lamp chamber having a portion offset therefrom and open to direct rays of light to the floor, said hollow leg constituting a conduit for the circuit wires, substantially as described. 45

4. In a chair, the combination with a lamp chamber having an open side, a plate hinged in the chamber and carrying a lamp, a hinged closure plate for the open side of the chamber and having an open light-directing portion, said closure plate on being opened clearing the way to allow said lamp holding plate to be opened, substantially as described.

5. In a chair, the combination with a 55 standard having a hollow leg, of a lamp chamber communicating with said hollow leg, a plate hinged in the chamber and carrying a lamp, circuit wires extending through said hollow leg to said lamp, and 60 a closure plate for said lamp chamber having a light directing portion, substantially as described.

6. In a chair, the combination with a standard having a hollow leg, of a lamp chamber 65 communicating with said hollow leg, a hinged plate closing communication between said hollow leg and said chamber, a lamp on said plate, circuit wires extending through said hollow leg to said lamp, a 70 plate hinged to the standard for closing the lamp chamber, and an outwardly offset portion on said plate for directing light from said chamber to the floor, substantially as described. 75

In testimony whereof I have signed my name to this specification.

JOSEPH B. KAUSAL.

DISCLAIMER

1,575,690.—*Joseph B. Kausal*, Chicago, Ill. AISLE CHAIR. Patent dated March 9, 1926. Disclaimer filed April 9, 1932, by the patentee.

Hereby enters this disclaimer to that part of the claims in said specification, embodying claims 2 and 5 thereof, which are in the following words:

“2. A chair having a lamp chamber therein, a reflector in the chamber having a downwardly and outwardly inclined bottom, a lamp arranged in the chamber, and an outwardly offset light-directing part opposite said inclined bottom and having an opening exteriorly of the chamber, substantially as described.”

“5. In a chair, the combination with a standard having a hollow leg, of a lamp chamber communicating with said hollow leg, a plate hinged in the chamber and carrying a lamp, circuit wires extending through said hollow leg to said lamp, and a closure plate for said lamp chamber having a light directing portion, substantially as described.”
